United States Patent Office.

JAMES F. MORSE, OF MONTGOMERY, ILLINOIS.

Letters Patent No. 77,640, dated May 5, 1868.

IMPROVED EXTENSION-LADDER.

The Schedule referred to in these Letters Patent and making part of the same.

TO ALL WHOM IT MAY CONCERN:

Be it known that I, JAMES F. MORSE, of Montgomery, in the county of Kane, and State of Illinois, have invented a new and useful Improvement in Extension-Ladders; and I do hereby declare and make known that the following is a full, clear, and exact description of the same, reference being had to the accompanying drawings, and the letters and figures marked thereon, which form part of this specification.

My said invention consists in a novel arrangement of mechanical devices in connection with a ladder constructed in two parts or members, one susceptible of being moved up and down upon the other for the purpose of lengthening or shortening the ladder, whereby the upper or sliding member of the ladder may be moved up or down, as desired, when the person using the ladder is standing upon the sliding member, thus enabling him to adjust the ladder with great accuracy and ease, and avoiding the trouble and loss of time incident upon descending from the ladder for the purpose of adjusting it to the desired length, as is necessary with all other extension-ladders now in use.

To enable those skilled in the art to understand how to construct and use my invention, I will proceed to describe the same with particularity, making reference in so doing to the aforesaid drawings, in which—

Figure 1 represents a front elevation of my invention.

Figure 2, a side view or elevation of the same,

Figure 3 a side sectional view thereof, and

Figure 4 a transverse section of the same.

Similar letters of reference in the several figures denote the same parts of my invention.

A represents the lower member of the ladder, which rests upon the ground, provided with the usual rungs steps marked *c*; B representing the adjustable or sliding member, provided with rungs or steps *d* in the usual manner.

The sliding member is of such width, with respect to the stationary member, as to fit within the standards A, and is secured in such position by means of the tongues *b* upon the standards B, which enter the corresponding longitudinal grooves *a* in the standards A, as clearly shown in fig. 4, so that the member B has a free reciprocating or sliding movement upon and in the member A.

The upper end of the member B is provided with the rollers C C, to facilitate the upward or downward movement of the same upon the wall or other surface against which the ladder may be raised.

To one of the upper rungs of the stationary member A are attached, upon each side of the ladder, as shown, the cords *m m*, which, passing down beneath the sheaves E E upon the lower end of the member B, go up and are secured to a transverse shaft or axle, D, arranged at the upper end of said member B, which shaft, by means of a crank-shaft, H I, and the gear-wheels F G, can be readily revolved, so as to wind up the cords *m* upon it, when desired, by a person standing upon any of the rungs *d*, provided he can reach the handle I.

J represents a ratchet-wheel fixed upon the shaft H, into which a pawl, P, is held by the action of a spring, S, and thus holds the member B securely in any position, or at any elevation to which it may be raised.

When the person upon the ladder wishes to shorten the same, by simply withdrawing the pawl from the ratchet-wheel, his own weight will cause the member B to descend to the required position, when, by releasing the pawl, the descent is checked, as desired.

Having described the nature, construction, and operation of my invention, I will now specify what I claim and desire to secure by Letters Patent.

I claim, in combination with the members A B of the ladder, the arrangement of the pulleys E, cords *m m*, shaft D, and gearing F G, whereby the operator can raise and lower the upper member of the ladder when standing upon the same, substantially as specified and shown.

JAMES F. MORSE.
